UNITED STATES PATENT OFFICE.

JAMES W. FALK, OF LITTLE FALLS, MINNESOTA.

TIE.

Application filed July 25, 1922. Serial No. 577,387.

To all whom it may concern:

Be it known that I, JAMES W. FALK, a citizen of the United States, residing at Little Falls, in the county of Morrison and 5 State of Minnesota, have invented new and useful Improvements in Ties, of which the following is a specification.

This invention relates to railroad ties, and has for its chief characteristic the provision 10 of means for clamping the rail, which means is constructed so that it can be adjusted from time to time, as the rail wears down into the wooden cushioning element, and thereby hold the rail immovable.

15 In carrying out the invention, I also provide a sectional tie, wherein the respective sections are not only reinforced by the elements which are utilized to detachably connect the sections together, but they are each 20 further reinforced by a metallic member which is designed to receive and support the wooden cushioning element above referred to.

The nature and advantages of the invention 25 will be better understood when the following detailed description is read in connection with the accompanying drawings, the invention residing in the construction, combination, and arrangement of parts as 30 claimed.

In the drawings forming part of this application, like numerals of reference indicate similar parts in the several views, and wherein:—

35 Figure 1 is a side elevation of the tie.
Figure 2 is a top plan view.

Figure 3 is a longitudinal sectional view through one of the tie sections.

40 Figure 4 is a sectional view taken at a right angle to Figure 3.

Figure 5 is a detail view of the rail clamp.

Figure 6 is a detail view of the key.

45 Figure 7 is a top plan view of one of the tie sections showing by dotted lines the position of the parts embedded in said section.

Figure 8 is a fragmentary view of the casting showing the shoulder and the space therebetween for accommodating the tie clamp.

50 Referring to the drawings in detail, 10 and 11 indicate respectively the tie sections, each of which is formed from concrete, and reinforced by spaced parallel metallic members 12 and 13 respectively, which have their opposite ends extended upwardly and curved toward each other as shown. Also

embedded in each tie section, and arranged between the elements 12 and 13, is a combined reinforcing and connecting element 14 which is provided with one or more openings 16 to accommodate right angularly disposed members 17, a construction which holds the reinforcing elements 14 immovably associated with the tie sections. One of these elements 14 projects beyond one end 60 of its respective tie section and terminates in a yoke-like portion 18, and the corresponding extremity of the reinforcing element 14 of the other section of the tie is threaded into this yoke-like portion 18, and 65 has associated therewith a nut 20. In this manner, the tie sections 10 and 11 are detachably connected together.

Embedded in each tie section is a metallic casting 22 which is formed with a recess 23, 75 which opens at the upper side of the section, this casting lying flush with the upper surface of the said sections as illustrated. This casting constitutes a cushion support, inasmuch as the wooden cushioning element 24 is 80 adapted to be received by the recess 23 to support the rail 25. This cushion support is provided with pointed projections 26 rising from the bottom of the recess 23 and adapted to be embedded in the cushioning 85 element 24. The casting 22 at one side of the cushioning element is provided with a groove 27, which is adapted to receive a key 28, the key being wider than the groove and adapted to bear against the rear wall of the 90 latter and the adjacent side of the cushioning element, and the adjacent edge of the base of the rail. The recess 23 is considerably wider than the cushioning element 24, to provide a space 29 at one side of the cushioning element for the tie clamp 30, the 95 clamp being arranged to move within this space when it is adjusted downwardly into effective engagement with the base of the rail. The tie clamp 30 is of usual construction, and is slidably supported upon a threaded bolt 31, the latter having a T-head 32 which is arranged between one side of the cushioning element 24, and a shoulder 33 formed on the casting 22. Arranged above the clamp 30 and adjustably associated with the bolt 31, is a nut 34, which when adjusted or threaded downwardly on the bolt, forces the clamp 30 down into effective engagement with the base of the rail, and holds 100 the rail immovably positioned upon the cushioning element. The casting 22 is pro- 105

vided with an opening 35 at a point beneath the cushioning to accommodate the cushion key 36.

While it is believed that from the foregoing description, the nature and advantages of the invention will be readily apparent, I desire to have it understood that I do not limit myself to what is herein shown and described, and that such changes may be resorted to when desired as fall within the scope of what is claimed.

What I claim is:—

1. A concrete tie, a metallic casting embedded in said tie and lying flush with the upper surface thereof, said casting having a recess, a cushioning element arranged in said recess, a pin interposed between one side of the cushioning element and one wall of the recess, said recess being wider than the cushioning element and provided with a space at the opposite side of said element, a threaded bolt arranged in said space, a rail clamp slidable on said bolt, and a nut associated with the bolt and bearing against said clamp, whereby the latter can be moved

downwardly in said space into effective engagement with the base of the rail incident to the wear of the cushioning element.

2. A concrete tie, a metallic casting embedded in said tie and lying flush with the upper surface thereof, said casting having a recess, a wooden block arranged in the recess to support the rail, said casting having a vertical groove, a pin slidable in said groove and arranged to bear against the casting and the adjacent side of said block, and said recess being wider than the block to provide a space at the opposite side thereof, a threaded bolt arranged in said space and having a T-head, a shoulder formed in said recess, the head of said bolt being interposed between the shoulder and the adjacent side of the block, a rail clamp slidable on the bolt and adapted to be moved downwardly in said space into effective engagement with the base of the rail, incident to the wear of the block, and a nut adjustable on the bolt and bearing against said clamp.

In testimony whereof I affix my signature.
JAMES W. FALK.
